UNITED STATES PATENT OFFICE.

LEONARD B. CHUBBUCK, OF HAMILTON, ONTARIO, CANADA, ASSIGNOR TO WESTINGHOUSE ELECTRIC & MANUFACTURING COMPANY, A CORPORATION OF PENNSYLVANIA.

DISCONNECTING SWITCH LATCH.

Application filed July 15, 1920. Serial No. 396,576.

To all whom it may concern:

Be it known that I, LEONARD B. CHUBBUCK, a subject of the King of Great Britain, and a resident of Hamilton, in the 5 Province of Ontario, Canada, have invented a new and useful Improvement in Disconnecting Switch Latches, of which the following is a specification.

My invention relates to switches and particularly to knife-blade switches such as are employed in connecting the bus bars of a generating station to the service leads or in other high-tension service. Such switches are infrequently operated and are usually 10 devoid of handles, the blades being withdrawn from the contact jaws by means of a "hook-stick" or operating tool adapted to be inserted in holes or recesses in the blades.

It is well known that the electrical stresses 20 incident to the flow of current through the jaws and blades of knife-blade switches tend to move the blades out of engagement with the jaws. Under abnormal or overload conditions, these stresses are frequently sufficient to thrust the switch-blade out of the 25 jaws and thus open the circuit.

Switches of this type are usually provided with latching devices for holding the blades in operative engagement with the 30 jaws. Such latching devices are usually designed to be released manually by an operating tool which is usually inserted in a recess in the blade at the moment the switch is to be opened or closed.

One object of my invention is to provide 35 a switch-blade-latching means of simple and durable construction which automatically latches the blade in operative engagement with the jaws when it is moved into closed-circuit position and which may be released by a single withdrawing movement of the operating tool tending to pull the blade out of contact with the jaws.

Another object is to produce a compact 45 latch construction wherein the position of the latch is visible to the operator and wherein the spring employed for maintaining the latch in operative position is of ample proportions and capacity, simple to manufacture and easily assembled and renewed.

These and other objects are attained by means of apparatus embodying the features herein described and illustrated in the draw-

ings accompanying and forming a part 55 hereof, wherein:

Fig. 1 is a plan view of a switch embodying my invention.

Fig. 2 is a side elevation of the switch shown in Fig. 1.

Fig. 3 is a side elevation of the end of the blade and a portion of the jaws showing a modified form of latch stop especially adapted for use with the form of latch illustrated in Figs. 1 and 2 and upon a blade 60 employed in double-throw switch.

Referring to the drawings, the switch includes a pair of spaced insulator posts 5 and 6 mounted upon a base 7. The post 5 is provided with a jaw member 8 to which a conductor terminal 9 is connected. The jaw member 8 embodies two pairs of conductor strips 10 between which the blades 11 are clamped by means of a pivot bolt 12.

The blades 11 are disposed in spaced relation and are reinforced, intermediate their ends, by means of a block 13 held in place by a rivet 14. The free ends of the blades are connected by means of a latch stop 15 secured between them and are provided with 70 aligned perforations or openings 16 into which the hook 17 of an operating rod 18 (shown in Fig. 2) may be inserted.

Upon the post 6 is mounted a contact jaw member 19 comprising two pairs of spaced 80 contact strips 20 disposed in parallel relation so that the spaces between them are in the planes of the blades 11 in order to receive the blades when they are moved into circuit-closing position. The contact jaw member 19 is provided with a terminal 21 which, for the purpose of illustration, may be assumed to be connected to a service lead. The blade 11, therefore, constitutes a connecting link between the terminals 9 85 and 21. The blade is adapted to be moved into open and into closed position by means of the operating tool 18. In order to maintain the blade in operative engagement with the contact jaws, I provide the jaws with a latch 22 which is pivoted between the pairs of strips 20 upon a shaft 23 extending through the bases of the strips. The latch is provided with a tooth 24 adapted to slip 90 over the ledge 25 on the outer and inner corner of the latch stop 15, when the blade has been moved into operative position, as 95 shown in Fig. 2. The outer end of the 100 105

latch is rounded at 26 so that it will be forced toward the pivot jaws by engagement with the round inner corner 27 of the stop 15 when the blade is moved into operative engagement with the contact jaws.

In Fig. 3, I have shown a latch stop 15' which is provided with similar oppositely disposed corners or ledges 27', either one of which may serve to retract a latch. This form of stop is especially well adapted for use with a blade of the double-throw type wherein two contact jaw members are employed which are adapted to be separately engaged by the same knife blade. A separate latch is provided in each contact jaw and is adapted to be retracted by the stop 15'.

In the form of switch illustrated in Figs. 1 and 2 a leaf spring 28 is mounted between the pairs of strips 20 and is retained in operative position in contact with the latch 22 by means of a pair of screws 29 which assist in holding the strips 20 in assembled relation and which project into the space between the pairs of jaws. This spring automatically snaps the latch into the position illustrated in Fig. 2 when the blade has been moved to operative position in the jaws and retains the latch in contact with the blade so as to prevent expulsion of the blade from the jaws.

When it is desired to withdraw the blade from the contact jaws the operating tool is inserted in the opening or recess 16 and moved in a direction tending to move the end of the blade out of the jaws. Movement of the blade is not possible, however, until the latch 22 has been moved to release position, in opposition to the tension of the spring 28. For the purpose of making this action incident to the blade-withdrawing movement of the operating tool, I provide the outer edge of the latch 22 with an upwardly inclined surface 30 which projects across the recess 16 in such manner that the hook of the operating tool may be inserted within the recess beneath the inclined surface. Outward blade-withdrawing movement of the operating tool moves the latch into release position, after which operation

the blade is free to be withdrawn from the contact jaws by further movement of the operating tool.

When the blade is moved to closed-circuit position, the corner 27 of the stop 15 first 55 engages the rounded surface 26 of the outer end of the latch and forces the latch aside to permit the entrance of the blade into the jaws.

The outward movement of the latch 22 60 is limited by a stop 31 provided upon the inner end of the latch, adapted to engage the base of the jaws.

While I have described and illustrated but two embodiments of my invention, it 65 will be apparent to those skilled in the art that various modifications, changes, substitutions, additions and omissions may be made in the apparatus described without departing from the spirit and scope of the invention as set forth in the appended claim.

I claim as my invention:

A switch comprising a pair of blades, a latch stop connecting the blades at one end and disposed between the blades so as to 75 hold them in spaced relation, contact jaws comprising spaced contact members for receiving the blades, the said blades being provided with a recess adjacent the end of the blade into which an operating tool may 80 be inserted for withdrawing the blade from the jaws, a latch pivoted to the jaws and extending between the blades and provided with a tooth for engaging the said latch stop when the blade is moved into operative 85 position, a spring mounted between the contact members and projecting between said blades and engaging the latch for normally holding the latch in operative engagement with the latch stop, the said latch extending across the recess in the blades and adapted to be engaged by the operating tool and withdrawn from engagement with the latch stop when the rod is 90 moved in a direction tending to withdraw the blade from the jaws.

In testimony whereof, I have hereunto subscribed my name this 28 day of June, 1920.

LEONARD B. CHUBBUCK.
